UNITED STATES PATENT OFFICE.

FREDRICH OLSEN, OF WASHINGTON, DISTRICT OF COLUMBIA.

DETONATING OR DISRUPTIVE EXPLOSIVE.

1,376,030.

Specification of Letters Patent. Patented Apr. 26, 1921.

No Drawing.

Application filed January 15, 1921. Serial No. 437,580.

To all whom it may concern:

Be it known that I, FREDRICH OLSEN, a subject of the King of Great Britain, and a resident of Washington, in the District of Columbia, have invented an Improvement in Detonating or Disruptive Explosives, of which the following is a specification.

The subject of this invention is a detonating or disruptive explosive intended for use 10 in blasting and for like purposes.

There are times, especially at the termination of a war when large quantities of certain materials, such as nitro-starch explosives and propellant powders (smokeless 15 powders and cordite) are on hand which are subject to more or less rapid deterioration and, consequently, can not be stored away for future use, and which have no commercial field or value and consequently 20 can not readily be disposed of.

The main object of the present invention is, therefore, the conversion of such materials into useful commercial products so that the same, instead of being classed as waste 25 may be readily disposed of and converted to commercial uses.

With these and other objects in view the invention resides in the novel combination of ingredients hereinafter described and 30 claimed, it being understood that changes in the precise embodiment of the invention herein disclosed may be made within the scope of what is claimed without departing from the spirit of the invention.

35 In carrying out my invention I take the well known nitro-starch explosives (Trojan grenade explosives, Trojan trench mortar shell explosives or grenade) and mix it with a propellant powder such as smokeless powder 40 or cordite in the proportions, 10 to 90 parts of nitro-starch explosives to 90 to 10 parts propellant powder.

In preparing the smokeless powder I prefer to grind the same to such a degree of 45 fineness that 100% will pass through a standard 20 mesh sieve, and at least 50% through a 50 mesh sieve. While this grinding is desirable and more satisfactory, re-

sults are obtained thereby, it is not absolutely essential.

50 The nitro-starch explosives mentioned are usually composed of nitro-starch, and an inorganic nitrate as ammonium or sodium nitrate, a carbonaceous substance, for instance charcoal and a stabilizer or anti-acid, as diphenylamin.

Instead of nitro-starch explosives nitro-starch may be used and mixed with the propellant powders in the proportions mentioned.

60 From the foregoing it will be evident that a field for the disposal of large quantities of nitro-starch explosives and propellant powders is provided, thus avoiding the waste due to deterioration of the nitro-starch explosives which is rather rapid because of its absorption of moisture.

Having described my invention what I claim as new and desire to secure by Letters Patent is:

70 1. The herein described composition of matter, containing a nitro-starch explosive and a propellant powder.

2. The herein described composition of matter, containing a propellant powder, a 75 nitro-starch, an inorganic nitrate, a carbonaceous material, and a stabilizer or anti-acid.

3. The herein described composition of matter, containing a propellant powder, nitro-starch, an inorganic nitrate, and a carbonaceous material.

4. The herein described composition of matter, containing a propellant powder, nitro-starch, an inorganic nitrate and a stabilizer or anti-acid.

5. The herein described composition of matter, containing a propellant powder, nitro-starch, and an inorganic nitrate.

6. The herein described composition of matter containing a propellant powder, nitro-starch, and a stabilizer or anti-acid.

7. The herein described composition of matter containing a propellant powder and nitro-starch.

FREDRICH OLSEN.
